UNITED STATES PATENT OFFICE.

THOMAS G. PAULSON, OF ESTELLINE, SOUTH DAKOTA.

TRACTION-ENGINE.

SPECIFICATION forming part of Letters Patent No. 695,387, dated March 11, 1902.

Application filed November 9, 1901. Serial No. 81,710. (No model.)

To all whom it may concern:

Be it known that I, THOMAS G. PAULSON, a citizen of the United States, residing at and whose post-office address is Estelline, in the 5 county of Hamlin and State of South Dakota, have invented new and useful Improvements in Traction-Engines, of which the following is a specification.

My invention has relation to improvements 10 in traction-engines; and the object is to provide a traction-engine mechanism which is simple in construction, effective in operation, and durable in use; also, which may be readily reversed in direction of movement, and in 15 which only a pair of intermeshing gears are employed in the propulsion of the engine and the same number in repulsion.

With these purposes in view my invention 20 consists in the novel construction of parts 20 and their arrangement and aggroupment in operative combination.

I have fully and clearly illustrated the 25 improvements in the accompanying drawings, forming a part of this specification, and wherein—

Figure 1 is a side elevation of a traction-engine embodying my improved constructions and wherein the boiler and steam-cylinder with piston-rod are indicated in dotted 30 lines. Fig. 2 is a top plan view of the machine, the steam-cylinder and piston-rod being shown in dotted lines. Fig. 3 is a longitudinal central section through the hub-sleeves and vertical section of the rear wheels, showing 35 the axle and the interposed compensating gearings. Fig. 4 is a central section through the compensating gear of the rear axle, and Fig. 5 is a detail view of the reversing-gears.

Referring to the drawings, 1 designates side 40 rails united at their ends by cross-pieces 2, the whole constituting a substantial rectangular frame upon which the boiler and propelling mechanism are mounted and carried. The front axle 3 carries the front end of the 45 frame and has the frame pivotally connected thereto by a substantial king-bolt 4. The axle is carried by wheels 5, turning on the spindles of the axle. Any preferred means may be utilized for steering the machine.

50 The rear wheels 6 are each mounted fixedly on sleeves 7, extending inwardly to approximately the middle of the rear axle 9,

and carry on their inner ends bevel-pinions 8, which are engaged by the beveled pinions of the compensating gear on the axle. The 55 rear axle or shaft 9 extends loosely through the sleeves 7 and is formed at its middle with a squared portion or block 10, provided with stud-bearings on its faces, on which are secured bevel-pinions 11, constituting a compensating gear, the pinions of which set between and mesh with the bevel-pinions 8 on the sleeves 7 to rotate the wheels 6 when the axle 9 is rotated, as indicated in Fig. 3 of the drawings.

It will be observed that the compensating gears rotate at the sleeves 7 as the axle rotates and under ordinary conditions of progression of the machine have no tendency to retardation of either wheel-sleeve. Both sections will 70 be driven forward synchronously, the compensating gears being revolved by the shaft without turning on their bearings; but when there is any retardation of either wheel, as when the engine makes a deviation from a 75 straight line and one wheel will turn slower than the other, the difference in their travel will be permitted and compensated for by the rotation of the gears on their bearings.

12 designates a shaft supported in bearings 80 a, secured to the side rails of the frame and having a crank-arm 13 mounted on one end thereof, and to the free end of the crank-arm 13 is pivotally connected one end of a connecting-rod 14, the other end of which is pivotally connected to the end of a crank-arm 15 on the projecting end of the axle and shaft 9, as indicated in the drawings.

Mounted on bearings b b' on the side rails of the frame is a crank-shaft 16, the crank 90 being located at the middle of the shaft, as shown, and to the wrist of the crank is connected the end of a piston-rod 20, operated by the steam-cylinder 19 of the engine, and whereby the mechanism is operated. On one 95 arm of the crank-shaft is loosely mounted a sleeve 36, having a limited sliding movement and having mounted on its outer end a pinion 17, which meshes with a large gear-wheel 18 on the shaft 12. On the inner end of the 100 sleeve 36 is formed or rigidly secured a tapering clutch-disk 34, which engages with frictional contact in a clutch 34^a, fixed on the crank-shaft and having a laterally-extending

annular flange within which the clutch-disk engages. A lever 38 is fulcrumed on a cross-piece 42 and engages the sleeve with its inner end in the usual well-known manner. A notched sector-rack 41 is secured to the cross-piece 42, in the notches of which the lever engages to hold the clutch in and out of engagement. It will be perceived from the foregoing that the mechanism described relates to and is all that is essential or required to effect the propulsion of the machine, and to effect this the clutch-disk is moved into engagement with the other member on the crank-shaft, the other portion or reversing mechanism standing disconnected and inactive.

The reversing mechanism will now be described. On the crank-shaft is mounted loosely and slidably a sleeve 36^a, carrying a clutch-disk 35 on its inner end, which engages with a clutch member 35^a, fixed on the crank-shaft, and on the outer end having a pinion 22. A lever 39, fulcrumed on the cross-piece 41 and engaging the hub of the clutch-disk, serves to move the clutch into and out of engagement. The pinion 22 meshes with an idle pinion 22^a, journaled on a stud-shaft secured at the proper point, and the pinion 22^a is engaged by the large gear-wheel 25, mounted loosely on the shaft 12 and the hub of which is formed with a clutch-face 26. On the shaft 12 is slidably mounted and to turn with the shaft a clutch sleeve or member 27, adapted to engage with the clutch-face on the hub of the gear-wheel 25, and thus cause the shaft to turn the wheel. The clutch-sleeve 27 is positively moved into and out of engagement with the other clutch member by means of a lever 27^a, mounted on a suitable support and provided with a trip-pawl 29, which engages in a sector-rack 30.

On the shaft 12 is formed a collar 32, between which and the inner end of the clutch member 27 is mounted an expansive spring 31, which when the lever is released tends to move and hold the clutch in engagement. On the end of the shaft 12 is fixed a crank-arm 13^a, having attached thereto the end of a connecting-rod 14^a, the other end of which is suitably connected to crank-arm 15^a, fixed to the end of shaft 9.

It will now be perceived from the foregoing description, taken in connection with the drawings, that when it is desired to reverse the direction of the machine from forward movement to backward movement the mechanism which is utilized to propel the machine forwardly is thrown out of gear by the lever

38, which moves the clutch member on sleeve 36 out of engagement, and the gears on that side of the machine are free to rotate without effecting the propulsion. The lever 39 is then utilized to make the clutch engagement on the reversing side of the machine, and then the lever 27^a is operated to throw the clutch member 27 into engagement with the member 26 of gear-wheel 25, and the reversal of direction of the machine becomes effective through the interposition of the idle pinion 22^a.

Having thus described my invention, what I claim as new, and desire to secure by Letters Patent, is—

1. In a traction-engine, the combination with a supporting-frame, of a driving crank-shaft, a sleeve loosely mounted on the crank-shaft having a limited sliding movement thereon, a clutch to lock the sleeve to the shaft, a pinion on the sleeve, a shaft journaled on the frame, provided with crank-arms at its ends, a gear-wheel on the latter-mentioned shaft, in mesh with said pinion, a rear axle having crank-arms, and formed with a middle square portion, wheels on the rear axle having inwardly-extending sleeves provided with bevel-pinions on their inner ends, and compensating pinions on the faces of the squared portion of the rear axle, and connecting-rods between the crank-arms, whereby the machine is moved forward.

2. In a traction-engine, the combination with a propelling mechanism adapted to be released in operative action of a reversing mechanism, comprising a supporting-frame, a driving crank-shaft, a shaft mounted on the frame, a rear axle, having a squared middle portion, said shaft and axle being provided with crank-arms at their ends, rods connecting the crank-arms, wheels mounted on sleeves on the rear axle and having their inner end formed with beveled pinions, beveled pinions journaled on the faces of the squared portion of the rear axle, a sleeve mounted on the crank-shaft and having a limited sliding motion thereon, a clutch to lock the sleeve to the crank-shaft, a pinion on the sleeve, an idle pinion with which the pinion on the sleeve meshes, a gear-wheel loosely mounted on the said shaft, and a clutch to lock the gear-wheel to turn with the shaft.

In testimony whereof I affix my signature in presence of two witnesses.

THOMAS G. PAULSON.
